Fig. 2.

UNITED STATES PATENT OFFICE.

ABRAM C. WISNER, OF JACKSON, MICHIGAN, ASSIGNOR TO REYNOLDS SPRING COMPANY, OF JACKSON, MICHIGAN.

SPRING STRUCTURE.

Application filed September 8, 1927. Serial No. 218,319.

This invention relates to spring structures.

One object of the invention resides in the provision of a device constructed for ready application to a base frame of common form 5 so as to secure the lower edge of an upholstery skirt to the common base frame to conceal and protect the skirt from wear at the lower edge of the base frame.

Another object is to provide a device constructed to embrace a portion of a base frame 10 of spring structures to strengthen the base frame and to secure the marginal edge of the upholstery skirt against the base frame to protect the skirt from abrasion and wear at 15 the lower edge of the base frame.

Another object is to provide a spring structure, embodying among other characteristics, means whereby to clamp the marginal edge of the upholstery skirt to the 20 outer side, top and bottom faces of the base frame comprising a suitable clamping member having a groove adapted to embrace the base frame and also having flanges, one to extend under the base frame and the other to extend upwardly beyond the horizontal 25 plane of the base frame, the groove being arranged at the juncture between said flanges and the clamping member being secured to the base frame by a pinching action on the 30 same whereby to secure the base frame and skirt and clamping member together.

A still further object is to provide a device for securing together a spring structure including a metallic base frame, and the 35 marginal edge of an upholstery skirt and a wood base upon which the upholstered spring structure is mounted.

With the above and other objects in view, the invention consists in the construction and 40 novel combination and arrangement of parts hereinafter fully described, illustrated in the accompanying drawings and pointed out in the claims hereto appended, it being understood that various changes in the form, proportion and minor details of construction, 45 within the scope of the claims, may be resorted to without departing from the spirit or sacrificing any of the advantages of the invention.

50 In the drawings:

Fig. 1 is a cross sectional view through a spring structure illustrating one form of the present invention applied thereto.

Fig. 2 is a top plan view of one form of 55 the invention unapplied.

Fig. 3 is a detail sectional view illustrating a modified form of clamping member.

Fig. 4 is a similar view showing the modified form of clamping member applied to a 60 wood base.

Referring now more particularly to the accompanying drawings, the reference character 5 indicates a continuous U-shaped sheet metal frame, having a groove 6 opening inwardly in a horizontal plane to receive 65 the lower convolutions of the border springs 7 which are held securely therein by pinching or compressing the metal of the frame 5 onto the lower convolutions of the border springs, as indicated at 8. This is an old 70 construction and the inner springs are generally supported on U-bars 9, being pinched therein, and the bars generally pinched at their ends onto the border springs 8.

The upholstery for spring structures for 75 vehicles and other purposes, generally consists of padding 10 and a covering 11, including a skirt 12. The lower marginal edge of the skirt 12 is secured to the metal base frame in various ways or to a wood 80 base frame if the metallic U-shaped frame is mounted on a wood base. In the present instance, and as shown in Figs. 1 and 2, I provide a clamping member formed to effect 85 a connection of the skirt with the metal base frame which strengthens the latter and also protects the lower edge of the skirt from 90 wear. For instance, as shown in Figs. 1 and 2, the skirt securing clamp may consist of a strip of sheet metal folded longitudinally upon itself to provide a lower flange 13 and an upwardly directed flange 14, with an intervening inwardly opening continuous longitudinal groove 15, the walls 95 of which project slightly outwardly beyond the flange 14, as shown. The groove 15 of the clamping member is adapted to receive the U-shaped frame 5 and binds the marginal edge of the skirt onto the U-shaped base frame. The upper edge of the flange 100 14 may be turned outwardly, as at 16, if desired, so as to obviate a sharp edge to prevent possible tearing of the upholstery skirt during application of the same, or when 105 the completed article is in use. If desired, the upwardly directed flange of the clamping member may be curved slightly, as indicated at 17 in Fig. 3, rather than as shown in Figs. 1 and 2, as it will perform the functions ascribed to the upwardly directed 110

flange shown in Figs. 1 and 2. In either form, the upwardly directed flange extends upwardly beyond the horizontal plane of the U-shaped base frame 5 and conceals and 5 protects that portion of the skirt which lies immediately above the base frame 5.

The spring structure having been built and it is desired to apply the upholstery covering, the latter is made up of the proper 10 size and placed over the structure. The marginal edge of the skirt is folded under the U-shaped base frame 5 and the clamping member described is applied to the base frame with the groove 15 of the clamping 15 member embracing the U-shaped base frame to bind and secure the marginal edge of the skirt over the base frame. The clamping member may have the upper and lower walls of its groove 15 pinched or compressed onto 20 the upper and lower walls of the groove 6 of the base frame 5 to provide for a more positive tight embracing relation between the clamping member and the base frame, than is afforded by depending merely upon 25 a snug tight fit of the walls of the groove 15 on the base frame. The clamping member may be pinched onto the base frame at intervals, as indicated at 18, or continuously, as may be desired.

30 As illustrated, the lower flange 13 of the clamping member extends inwardly beyond the U-shaped base frame 5 and gives added strength to the structure and takes the weight of the latter, giving greater width 35 to the base frame than that now afforded by the usual U-bar or U-shaped base frame, considerably strengthening the latter horizontally. The upwardly directed flange strengthens the base frame vertically. The 40 flange 14 and the lower flange 13 with the walls of the intervening groove 15 of the clamping member shield the marginal edge of the skirt and protect the same in use from wear incident to marring or abrasion 45 caused by friction between the seat structure and its support. The clamping member also gives an ornamental appearance to the upholstered structure.

In Fig. 4 there is illustrated a form of 50 the invention as applied to a wood base 19 and to provide for thus mounting the upholstered spring structure, the lower flange 13 of the clamping member may be provided with perforations 20 through which suitable 55 fastenings 21 may pass into the wood base 19 to secure the base frame 5, with the skirt applied thereto, to the wood base, obviating necessity of stapling the base frame 5 or convolutions of border springs to the 60 wood base. The perforations 20 need not be formed in the flange 13 to facilitate piercing of said flange by the fastenings, for suitable fastenings may be used to pierce the said flange and wood base, simply by driving 65 such fastenings through said flange into

the wood base as is well understood. In either event, the fastenings 21 pierce the flange 13 and serve to secure together the skirt, base frame and wood base, obviating necessity of pinching the walls of the groove 70 15 of the clamping member onto the base frame 5. In the forms shown in Figs. 1 to 3 inclusive, the embracing relation of the clamp groove with the U-shaped base frame 5, is such, owing to the flexibility of the 75 sheet metal of which the base frame and clamping members are formed, as to provide for an effective tight connection for binding the skirt onto the base frame as to obviate the necessity of pinching or compressing the 80 walls of the groove 15 onto the base frame, as aforesaid, especially in view of the ends of the clamping member being secured together by pinching or indenting the metal 85 at abutting ends, as indicated at 22.

Thus it will be seen that the marginal edge of the skirt is tightly and effectively secured to the base frame by means which not only effects the tight and effective connection but gives great strength to the sheet metal base frame to prevent kinking or bending of the latter in use, said means effecting stability 90 up and down and in and out with relation to the sheet metal base frame. It is apparent also that the marginal edge of the skirt is wrapped or passed over the base frame in such a manner as to be clamped thereon at at least three points, that is, it is pressed against the base frame at the top and bottom of the latter and also at the bight portion or outer wall of the same.

95 What is claimed is:

1. Means adapted to connect the marginal edge of an upholstery skirt of a spring structure to the base frame of the latter, comprising a strip of sheet metal folded longitudinally upon itself to provide spaced flanges and an inwardly opening longitudinal groove arranged at the juncture between said flanges, said strip being bendable to conform to the contour of the base frame and to embrace the latter, said strip having one flange adapted to extend under the base frame of the spring structure and having its other flange extending upwardly vertically above the base frame and arranged contiguous to the skirt to form a guard to shield the skirt a substantial distance above the base frame to prevent wear at the lower edge of the skirt, both flanges being unslotted, the strip having its free ends overlapping and where overlapped being secured together to thereby secure the strip tightly on to the base frame and bind the marginal edge of the skirt tightly against the base frame.

115 2. Means adapted to connect the marginal edge of an upholstery skirt of a spring structure to the base frame of the latter, comprising a strip of sheet metal folded lon-

gitudinally upon itself to provide spaced flanges and an inwardly opening longitudinal groove arranged at the juncture between said flanges, said strip being bendable to 5 conform to the contour of the base frame and to embrace the latter, said strip having one flange adapted to extend under the base frame of the spring structure and having its other flange extending upwardly vertically 10 above the base frame and arranged contiguous to the skirt to form a guard to shield the skirt a substantial distance above the base frame to prevent wear at the lower edge of the skirt, both flanges being unslotted, the strip having its free ends overlapping and where overlapped being secured together to thereby secure the strip tightly 15 on to the base frame and bind the marginal edge of the skirt tightly against the base frame, the flange which extends under the spring structure being bent at intervals by pinching of the metal to bind such flange against the inner side of the base frame, and thereby cooperate with the securing 20 means at the overlapping ends of the strip to prevent detachment of the strip from the spring structure.

3. Means adapted to connect the marginal edge of an upholstery skirt of a spring structure to the base frame of the latter, comprising a strip of sheet metal folded longitudinally upon itself to provide spaced flanges and an inwardly opening longitudi-

nal groove arranged at the juncture between said flanges, said strip being bendable to 35 conform to the contour of the base frame and to embrace the latter, said strip having one flange adapted to extend under the base frame of the spring structure and having its other flange extending upwardly vertically 40 above the base frame and arranged contiguous to the skirt to form a guard to shield the skirt a substantial distance above the base frame to prevent wear at the lower edge of the skirt, both flanges being unslotted, the strip having its free ends overlapping and where overlapped being secured together to thereby secure the strip tightly 45 on to the base frame and bind the marginal edge of the skirt tightly against the base 50 frame, the flange which extends under the spring structure being bent at intervals by pinching of the metal to bind such flange against the inner side of the base frame, and thereby cooperate with the securing 55 means at the overlapping ends of the strip to prevent detachment of the strip from the spring structure, and the strip being pinched along the outer side of the groove so as to bind the marginal edge of the skirt between 60 the walls of the groove and the base frame of the spring structure.

In testimony whereof, I have hereunto set my hand.

ABRAM C. WISNER.
